UNITED STATES PATENT OFFICE.

LOUIS WOJIDKOW, OF BROOKLYN, NEW YORK.

DESIGN FOR A KETTLE-STAND.

SPECIFICATION forming part of Design No. 25,477, dated May 12, 1896.

Application filed April 11, 1896. Serial No. 587,222. Term of patent 3½ years.

To all whom it may concern:

Be it known that I, LOUIS WOJIDKOW, a citizen of the United States, residing at Brooklyn, in the county of Kings and State of New York, 5 have invented and produced a new and original Design for a Stand for Kettles, of which the following is a specification, reference being had to the accompanying drawing, which shows a perspective view of the same.

10 The leading feature of my design consists of an upper larger ring and a lower smaller ring supported by curved legs, the upper end of each of which is somewhat broadened and formed into the shape of a leaf, said legs decreasing in width toward the foot, a single curved bracket extending from said leg to the 15 lower ring.

A represents the upper larger ring, B the lower ring, and C the legs, each of the latter being curved, as shown, and having its upper end D broadened and so decorated as to give it the appearance of a leaf. From the upper leaf-like end the leg decreases in width toward the foot E, a curved bracket F extending from each of said legs to the lower ring B. 20 25

What I claim is—

The design for a kettle-stand substantially as herein shown and described.

LOUIS WOJIDKOW.
